LAMP FOR A WELDING MASK

Richard W. Henes, Phoenix, Ariz., assignor to Henes Manufacturing Company, Inc., Phoenix, Ariz.

Filed Aug. 3, 1964, Ser. No. 81,119

Term of patent 14 years

(Cl. D48—26)

FIG. 1 is a perspective view of a lamp for a welding mask shown mounted on a welding helmet and illustrating my new lamp design;

FIG. 2 is an enlarged front view of the lamp shown in FIG. 1;

FIG. 3 is an enlarged side view of the lamp taken on line 3—3 of FIG. 1, and

FIG. 4 is an enlarged back view of the lamp.

The showing of a welding mask and screws is for illustrative purposes only.

The cord in FIG. 1 and the cord clamps in FIG. 4 have been shown broken away to show indeterminate length and for convenience of illustration respectively.

I claim:

The ornamental design for a lamp for a welding mask, as shown and described.
